(57) **CLAIM**

The ornamental design for a linear shelf light fixture with reflectors, as shown and described.

DESCRIPTION

FIGS. 1A-B are a bottom perspective view of a light fixture according to an embodiment of the present invention.

FIG. 2 is a right end elevation view thereof, with the left end being identical.

FIGS. 3A-B are a top plan view thereof.

FIGS. 4A-B are a right side elevation view thereof, with the left side being identical.

FIGS. 5A-B are a bottom plan view thereof.

FIGS. 6A-D are a bottom perspective view of a light fixture according to an embodiment of the present invention.

FIG. 7 is a right end elevation view thereof, with the left end being identical.

FIGS. 8A-D are a top plan view thereof.

FIGS. 9A-D are a right side elevation view thereof, with the left side being identical; and,

FIGS. 10A-D are a bottom plan view thereof.

The broken lines shown on the drawing figures represent portions of the light fixture that form no part of the claimed design.
